UNITED STATES PATENT OFFICE.

CHARLES E. ERICKSON, OF DELTA, UTAH, AND MATTHEW JAMES MAST, OF GRAND JUNCTION, COLORADO.

GOLD-PANNING MACHINE.

Application filed November 26, 1921. Serial No. 517,868.

To all whom it may concern:

Be it known that we, CHARLES E. ERICKSON, residing at Delta, in the county of Millard and State of Utah, and MATTHEW J. MAST, residing at Grand Junction, in the county of Mesa and State of Colorado, both citizens of the United States, have invented certain new and useful Improvements in Gold-Panning Machines; and we do hereby declare the following to be a full, clear, and exact description of the invention, such as will enable others skilled in the art to which it appertains to make and use the same.

This invention relates to apparatus for separating precious metal, such as gold, from the medium containing the same and designed chiefly for recovering the gold from sand.

The invention provides an apparatus for separating fine gold, inclusive of flour gold, from sand which has run through a sluice box and screen, the apparatus includes a substantial frame, a pan or elongated shallow box supported on the frame by hangers and having a corrugated copper bottom amalgamated on its upper side and containing deflectors and means for imparting a vibratory and jarring motion to the pan.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a side view of a gold panning machine embodying the invention,

Figure 2 is a vertical central longitudinal section thereof,

Figure 3 is a top plan view of the same,

Figure 4 is an end view,

Figure 5 a transverse section on the line 5—5 of Figure 3, and

Figure 6 is a sectional detail of the bumper.

Corresponding and like parts are referred to in the following description and designated in the several views of the drawings by like reference characters.

The apparatus or machine comprises a

substantial frame including a base 1, end uprights 2 and 3 and an intermediate upright 4, the several parts being braced and connected in any preferred way. A pan or box is mounted upon the frame to admit of a reciprocatory movement being imparted thereto. Hangers 6 connect the opposite end portions of the pan or box 5 with the uprights 2 and 4. A transverse shaft 7 mounted upon the base portion 1 of the frame is provided with a plurality of cam portions 8 which are in cooperative relation with the pan or box 5 to impart a reciprocating movement thereto. The shaft 7 may be driven from a suitable source of power, not shown, in any well known manner. A bumper 9 is mounted on the end upright 3 and is positioned to receive the impact of the pan or box 5 at each return movement thereof whereby to impart a jar to the pan or box to insure positive agitation of the material passing therethrough so as to effect separation of the precious metal from the pan. The material is supplied to the pan or box 5 by means of a sluice 10 and the tailings escape by means of a chute or outlet 11.

The pan or box comprises an elongated frame of rectangular form having a bottom of sheet copper which is transversely corrugated to form upwardly curved portions 12 and depressions 13. The relatively forward portions of the upwardly curved part 12 are gradually curved whereas the rear portions are abrupt whereby to provide a quick descent for the material which facilitates the separation of the precious metal therefrom. Moreover by having the rear portions abrupt they offer a greater resistance to the return of the material at each forward movement of the pan or box. The hangers 6 have a relative disposition to normally hold the pan in engagement with the bumper 9. The cams or tappets 8 move the pan or box 5 forwardly and upon clearing the pan the latter returns to normal position by gravitational action the impact being sustained by the bumper 9 and the resultant jar serving to advance the material over the upwardly curved portions 12 of the bottom of the pan. The material agitated and advanced thereby materially assists in separating the metal from the sand. Deflectors or baffles 14 are located in the upper portion of the pan or box directly in line with the depressions or channels 13.

thereby compelling any flour gold to be moved downwardly in order to pass by the baffles or deflectors. The upper surface of the copper bottom is coated with amalgam 5 whereby to absorb and separate the particles of gold from the sand or other material containing the same. The spent water and tailings pass off through the outlet 11.

The pan is provided with a cross piece 15 10 which is engaged by the tappets 8, the latter consisting of projections at the outer edges of disks 16 secured to the shaft 7.

The bumper 9 may be of any construction and, as shown, it consists of an impact piece 15 a having a stem upon which is fitted a spring b enclosed in a guide c. The stem of the impact piece a operates in an opening d formed in the upright 3.

Having thus described the invention, what 20 we claim is:—

A separator of the character specified comprising a frame, a pan having a corrugated copper bottom coated upon its upper side

with amalgam, deflectors in the upper portion of the pan in line with the depressions 25 between the upwardly curved portions of the corrugations, hangers forming suspending means between the pan and frame and normally inclined to the vertical, means for imparting an intimate forward movement 30 to the pan and a bumper for sustaining the impact of the pan upon its return movement and imparting a jar thereto.

In testimony whereof we affix our signatures in the presence of witnesses.

CHARLES E. ERICKSON.
MATTHEW JAMES MAST.

Witnesses to the signature of Charles E. Erickson:

ARTHUR C. COLE,
HOWARD H. CORN.
